UNITED STATES PATENT OFFICE.

EDOUARD BELIN, OF PARIS, FRANCE.

APPARATUS FOR TRANSMITTING TO A DISTANCE REAL OPTICAL IMAGES.

No. 853,755.

Specification of Letters Patent.

Patented May 14, 1907.

Application filed July 10, 1905. Serial No. 269,134.

To all whom it may concern:

Be it known that I, EDOUARD BELIN, a citizen of the Republic of France, engineer, whose full postal address is 60 Boulevard de 5 Clichy, Paris, France, have invented certain new and useful Improvements in the Apparatus for Transmitting to a Distance Real Optical Images, of which the following is a specification.

10 This invention consists in improvements in the method of and apparatus for the transmission to a distance of real optical images forming the subject of Patent 844,086, Feb. 12, 1907.

15 The present improvements relate more particularly: 1. To the combination as a whole of the apparatus for carrying out the method with the object of rendering its use more practical; 2. To an exclusively electrical means for enabling the image to be recorded by means of perforations formed in a band of suitable material.

Reference will now be made to the accompanying drawings in which:

25 Figure 1 is a diagrammatic view showing the combination as a whole; Fig. 2 shows diagrammatically the arrangement of the electric mechanism utilized for perforating the recording band. Fig. 3 is a detail on an enlarged scale of the essential part of this arrangement.

30 The system always comprises two stations, viz: a transmitting station and a receiving or recording station, but according to the improved arrangement, shown in Fig. 1, the transmitting apparatus A has the great advantage of only comprising a dark chamber 1 and a collector or multiple commutator 2, all the other parts being transferred to the receiving station. The transmitting apparatus also does not require the use of a local current, it simply utilizes the line current which may be very weak.

35 The chamber 1 has no particular improvement; it is provided with an objective 3 and contains a mirror by means of which the emergent luminous group of rays is projected on to selenium elements suitably arranged in the interior of the said chamber as shown in Fig. 1 of Patent 844,086. The ends of the metallic wire which enter into the constitution of each of these sensitive elements are respectively connected with terminals 4 and 5. The terminals 5 are in electric communication with one of the line wires 6 proceeding to the source of electricity 10.

Each of the terminals 4 is connected with one of the contact elements of the collector or multiple commutator 2 the object of which is to bring them successively into the line circuit. The second line wire 7 starts thus from the collector 2.

60 The receiving apparatus B comprises a special relay *g* similar to the relay *g* (Fig. 2) of Patent 844,086 above mentioned, and electro-magnet 9 and the recording apparatus proper. The line current brought by the wire 7 passes through one of the windings of the special relay 8 in the manner indicated in the patent hereinbefore mentioned, it then traverses the 70 coil of the electro-magnet 9 and the circuit is closed at 10 with the source of electricity after having passed through the switch 11.

According to the improved arrangement, a local current arising from a special source 12 75 is available at the receiving station. In this particular circuit which is represented by the wires 14 and 15 the second winding of the special relay 8 is arranged, also a switch 13, the receiving collector which always work synchronously with the transmitting collector 2, and finally the recording mechanism (printing and perforating apparatus.)

80 Working.—The moment the transmitting collector 2 brings a sensitive element of the chamber 1 into the line circuit, the latter is closed. As may be seen in patent 844,086 above mentioned, the intensity of the current necessarily varies according to the degree of illumination of the element placed in 90 circuit. When the intensity, by reason of the action of the special relay 8 which introduces into the line circuit an automatically variable resistance, is sufficient to excite the electro-magnet 9, the armature of this latter 95 is attracted, establishing contact at 13 and thus closing the local circuit of the receiving station. The local current then passes into the collecting apparatus of the receiver, but this current is itself variable according to the 100 position occupied by the windings of the special relay 8. The receiving collector now brings into the local circuit the recording mechanism corresponding to the selenium element in use and this mechanism works exactly under the same conditions as before. The electro-magnet 9, at the same time as it closes the circuit of the receiving station, breaks the line circuit by opening the switch 11. As the line current no longer passes 110 into the electro-magnet, this latter allows its armature to resume its initial position,

the switch 13 is opened and breaks the local circuit, while the line circuit is again closed by the closing of the switch 11. At this moment the collector 2 places in the line circuit another selenium element and the various phases which have just been described are renewed and so on successively.

In order to record the images transmitted, instead of utilizing printing cones, or perforations obtained by means of needles, an absolutely perfect recording is obtained by forming perforations in a suitable band by means of induction sparks which are caused to spring between the electrodes suitably arranged on the one side and on the other of the said band. It has in fact been noticed that if for instance, a sheet of paper be placed in the track of an induction spark, this latter forms a perforation therein. The perforations thus obtained are strictly circular and the diameter is proportionate to the variations of the induced current which has produced the spark. In order to employ this means of recording the real optical images transmitted by the system hereinbefore described, the arrangement shown in the drawings has been designed. Figs. 2 and 3 relate to this special arrangement. At the receiving station, an induction coil 18 is introduced in the local circuit passing through the special relay 8 and switch 13; in the secondary circuit constituted by the wires 16 and 17, starting from the coil 18, there is located the receiving collector or multiple commutator 19 which works synchronously with the collector 2 of the transmitting apparatus, also the perforating apparatus. This latter comprises on the one hand a certain number of points 22 (Fig. 3) insulated from one another and each having a terminal 20 which serves for connecting them electrically and respectively with one of the contact elements of the collector 19 which brings successively into the secondary circuit the point 22 corresponding to the selenium element for the time being placed in circuit by the transmitting collector 2 (Fig. 1.) On the other hand the arrangement is completed by a series of blades or strips 21 preferably insulated from one another and each arranged opposite a point 22 as shown in Fig. 2. They are provided with a terminal 23 and these latter are all connected with a suitable wire 17 of the secondary circuit. The receiving band 24 passes between the blades 21 and the extremities of the points 22. The apparatus being in action, when the magnet 9 attracts its armature in the manner hereinbefore indicated, the switch 13 is closed, the local current of the receiving station passes into the coil 18 which, in its turn, sends a current through the collector 19 to the perforating device *a*. At this moment, the collector 19 connects the desired point 22

and a spark springs between this point and 65 the blade 21 which faces it. This spark perforates the receiving band 24 and the hole produced has a diameter proportionate to the variations of the current causing the spark. This current varies, as the local current emanating from the source 12 itself varies according to the position of the contact rollers of the special relay 8 as has been already mentioned. A series of perforations varying in size according to the various selenium elements of the transmitting apparatus and consequently to the points of the real optical image which is to be reproduced at a distance as are thus obtained on the recording band 24. Of course the displacements of 80 the band 24 relative to the points 22 must be combined in such a way as to obtain a suitable registration of the images in the manner provided. 75

I claim as my invention 85

1. An improved system of transmitting to a distance real optical images, comprising a receiving station with recording apparatus and a transmitting station having a dark chamber with selenium elements therein and 90 a transmitting collector or multiple commutator, the receiving station being in the same electric circuit with the transmitting station, said receiving station having a relay adapted to cause a local current to undergo variations 95 of intensity proportional to the variations of intensity of the line current, in combination with a receiving collector through which the said local current passes for the purpose of operating the recording apparatus, said collector or multiple commutator moving synchronously with the commutator of the transmitting station. 100

2. In a system of transmitting to a distance real optical images, comprising a receiving station having a recording apparatus, comprising a band and means for forming perforations of variable diameter in the recording band by means of electric sparks, the diameter of the perforations being proportional to the current impulses arriving at the receiving station. 105

3. In a system of transmitting to a distance real optical images, comprising a receiving station having a recording apparatus, 115 comprising a band and means for forming perforations of variable diameter in the recording band by means of electric sparks, a secondary circuit having an induction coil excited by the current serving the receiving 120 station for producing the sparks, and a collector or multiple commutator in said station being arranged in the secondary circuit. 120

4. In a system for transmitting to a distance real optical images, an electric circuit 125 connecting a transmitter and a receiver, a transmitter by which currents automatically varying in intensity in proportion to differ-

ences in intensity of the light rays from the image are transmitted to the receiver, a receiver comprising a band and means actuated by said variable current for forming perforations therein of varying diameter proportioned to the variations in intensity of the current impulses received from the transmitter, substantially as described.

In testimony whereof I have signed my name to this specification, in the presence of two subscribing witnesses.
